FILE FOLDER ENVELOPE

Wilbur R. Chapel, Barrington, Ill.

Application August 31, 1942, Serial No. 456,737

7 Claims. (Cl. 129—16.7)

The present invention relates to file envelopes. The principal object of the invention is to provide a mailing envelope wherein booklets, catalogues, and various types of printed or written matter may be mailed, the envelope being so constructed as to provide an indexing file folder for filing the contents when they are received by the addressee.

I am aware that heretofore attempts have been made to provide envelopes which would serve additionally as file folders for indexing and filing away the contents thereof. My invention however distinguishes from such previous devices in that it provides a file envelope that is free of objectionable flaps or additional thicknesses of material when it is used as a file folder. The envelope is of such nature that it may be readily inspected by postal authorities for the reason that it is customary to mail most catalogues, printed matter and the like unsealed in order that they may be inspected by the postal authorities.

My invention further contemplates a novel file envelope wherein the receiver of the envelope may transform it into a file folder by a simple continuous separation of the sealing (multiple thickness) layers of the envelope from the remainder. In this connection the envelope is so arranged that in separating the edges having flaps folded over to make a pocket an index tab is created on at least one side edge of the folder. In certain forms of the invention this idea is carried further and the file folder is made with one wall longer than the other in order to expose the headings and dates of letters, etc., that may be filed in the folder. The resulting file folder created by the separating operation is in all respects substantially identical with the normal open file folder commonly used. It has only the front and back walls and these walls are of a single thickness. Furthermore, the file folder provided has at least a portion of one of the walls higher than the corresponding portion of the opposite wall for indexing purposes.

One of the important features of the present invention is the construction of the blank from which the file envelope is made and the reduction of waste material due to conversion of the envelope into a file folder. In its preferred form the file envelope comprises just enough sheet stock to form an envelope with narrow flaps along two or three sides of the envelope to effect the formation of a pocket and a closure flap. In the conversion of the envelope into a file folder by the recipient of the envelope the only lost

material comprises the parts of the envelope used to create the pocket and to provide a closure flap, the remaining portion of the envelope being no more than is absolutely necessary for the file folder. By my construction I maintain the thickness taken up by the file folder to essentially the same thickness that is taken up by a standard file folder having two opposing single ply walls. This is an important advantage in the saving of filing space.

The features and advantages of the invention will appear more fully as the description proceeds, reference being had to the accompanying drawings wherein a preferred form of the invention is shown. It is to be understood however that the drawings and description are illustrative only and that they should not be considered as limiting the invention except insofar as it is limited by the claims.

In the drawings:

Fig. 1 is a view in side elevation of the file envelope blank prior to its being folded into envelope shape;

Fig. 2 is a similar view showing the file envelope completed and closed ready for mailing;

Fig. 3 is a view in side elevation illustrating the file folder as it is completed by the separating operation, the separated parts being shown in conjunction with the folder;

Fig. 4 is a view taken from the opposite side from that of Fig. 3 showing only a portion of the file folder and the removed material;

Fig. 5 is a view in side elevation of a slightly modified form of the invention wherein the file envelope is so prepared as to provide a file folder with one wall longer than the other;

Fig. 6 is a view in side elevation of the file envelope shown in Fig. 5 but with the file folder portion separated from the envelope forming portions;

Fig. 7 is a sectional view on the line 7—7 of Fig. 5; and

Fig. 8 is a sectional view on the line 8—8 of Fig. 5.

Referring now in detail to the drawings, the file envelope blank shown in Fig. 1 comprises a flat sheet of envelope stock preferably of a grade that is sufficiently stiff to make good file folders. It will be noted that this sheet comprises a main body portion 10 creased along the line 11 to provide a fold line. The body portion is also provided with a closure flap 12 that extends along one end edge of the larger section 10a of the body. The meeting line of this closure flap with the portion 10a is perforated with

small die-cut perforations indicated at 13 so that the closure flap may be separated from the portion 10a. The perforations 13 curve into the portion 10a at the top thereof. Along the free edge of the portion 10a, opposite the fold line 11, a sealing flap 14 is provided. The material is creased at the junction 15 of the flap 14 with the portion 10a to facilitate folding of the flap. The flap 14 is of such a length as to overlap with the portion 10b of the body 10 when the portion 10b is folded against the portion 10a. A suitable adhesive is applied to the overlapped surfaces of the flap 14 and the portion 10b.

The portion 10b has a line of perforations 16 extending parallel to the edge that is overlapped by the flap 14, this line of perforations being substantially even with the edge of the flap 14. This line of perforations meets a similar line of perforations 17 that extends at right angles to it at a small distance from the side edge of the blank 10 remote from the flap 12. This line of perforations 17 extends from the line of perforations 16 in a direction parallel to the aforementioned edge of the blank 10 to a point adjacent to the junction of the flap 14 with the body portion 10a. The line of perforations curves as indicated at 18 and extends parallel to the crease 15 for a distance preferably somewhat more than one-half the distance to the edge of the portion 10a that carries the flap 12. The line of perforations then extends outwardly along a curved path as indicated at 19 to the crease 15 and follows the crease 15 for the rest of the way across the portion 10a. The line of perforations 17 separates the portions 10a and 10b from two sealing portions 20b and 20a that may be secured together by adhesive indicated on the portion 20b or by stapling to complete the envelope.

In making an envelope from the blank just described the portion 10b is first folded over along the fold line 11 and the portions 20a and 20b are secured together. The flap 14 is then folded over the edge of the portion 10b and adhered to it by the adhesive provided on the flap. An adhesive is also preferably provided on the inner surface of the flap 14 at one extreme end as indicated at 21 so that the flap 14 will adhere to the portion 20a of the body and complete the sealing of the end of the envelope. The envelope is then complete for reception of the contents that are to be mailed, after which the closure flap 12 may be inserted. The envelope is then ready for mailing.

When the addressee of the envelope receives it he may make a simple file folder of it by separating the portions 20b and 20a from the main body portion along the perforated line 17. The flap 14 has a perforation line 22 that forms a continuation of the line 17 from the point where the portion 10b is adhered to the flap. This line of perforations 22 follows the line of perforations 17 across the top of the envelope and joins it where the line of perforations coincides with the fold line 15. Thus by the one separating operation the envelope is opened up along one end and a portion of the top edge. The remainder of the flap 14 is then removed by separating it along the line of perforations 16 and the flap 12 is finally removed by separating it along the line of perforations 13. This provides a file folder with an index tab 23 on the back wall thereof and with the back wall longer than the front wall; in other words, an ordinary file folder. It will be noted that the thickness of material in the file folder is at no point more than the thick-

ness of the sheet stock from which the envelope is made. There are no loose edges of flaps remaining on the file folder to interfere with its use in the ordinary way.

Referring now to the slightly modified form of the invention, in this form of the invention the body portion 25 of the envelope comprises a blank similar in construction to the blank 10 but in this case the body portion is creased along its midpoint so that the front part 25a and back part 25b of the envelope are essentially the same in height. A closing flap 26 is attached to the back portion 25b at one end, there being a line of perforations 27 at the junction of the closing flap with the back portion.

A top flap 28 is connected to the back portion, this top flap being of the shape shown in Fig. 5. There is a line of perforations 29 between the top flap and the back portion 25b. The top flap is secured to the front portion 25a by a suitable adhesive.

At the side edge opposite to the flap 26 I provide another flap 30 on the back portion 25b, this flap being of a substantial width, that is, about 2" on a standard size envelope, for receiving letter size paper unfolded. The flap extends from the junction of the top flap with the back portion to the junction of the front portion with the back portion. A line of perforations 31 is provided along the junction of the flap 30 with the back portion. The flap 30 is folded over and adhered to the front portion 25a by suitable adhesive to complete the envelope.

The front portion 25a is provided with a line of perforations 32 beginning at the upper right-hand edge just below the top flap and following the top flap to the point 33 where the top flap is reduced in depth. At this point the line of perforations is curved upwardly and is continued as a line 34 to a curved portion 35 that extends down to the edge of the flap 30. The line of perforations then continues as the line 36 to the junction of the front portion 25a with the back portion 25b and thence as indicated at 37 along the junction line to the edge where the flap 30 is secured.

This particular construction provides a file envelope that has a front wall 25a that is not as long as the rear wall in a horizontal direction. It will be evident that by separating the top flap 28 by starting along the perforation lines 29 and 32 the flap 28 and the flap 30 and the adhered portions of the front wall 25a can be stripped off, leaving the back wall 25b straight along the top edge and along the left-hand edge with an index portion visible above the perforation line 32 and with the back wall slightly higher than the top wall, as is customary in file folders. The only additional step necessary to produce the final file folder is to remove the flap 26 by tearing along the line of perforations 27 that joins it to the back portion 25b. This file folder, in addition to having all of the characteristics of an ordinary file folder, including front and back walls of single thicknesses, has the front wall cut away sufficiently to leave the headings and the letters filed in the file holder exposed at the left-hand edge of the folder, as shown in Fig. 6. This form of the invention has all of the advantages of the first form and in addition the advantage just described. It calls attention to the presence or absence of contents within a folder and shows the nature of such contents.

It will be noted from an examination of the

drawings and from the description that the waste material involved in converting the envelope to a file folder is only that material which is used in securing the opposite portions of the envelope together and the material necessary for the closing flap. Where the closing flap is to be sealed it is contemplated to provide a separation line for removing the sealed part of the flap. The envelope itself utilizes no more material than an ordinary envelope yet the file folder obtained is of the ordinary size and is free of double thicknesses which would reduce the amount of filing in a given cabinet space. The file folder is also free of loose flaps that would be inconvenient in filing. By the utilization of this file envelope the amount of paper necessary for mailing and filing is cut to that necessary for the mailing of the printed matter. The envelope provides the file folder for the addressee.

Envelopes of this character also have the advantage of enabling the one who mails catalogues and circular information to originally print the proper indexing information directly on the envelope where it will appear as the indexing tab of the ultimate file folder. The indexing tab may be put anywhere along the edge. In fact the position and nature of the indexing tab may be varied to suit the needs of the trade. The file folder may be used with separate indexing tabs if desired. In addition the entire interior of the file folder or envelope is available for printing advertising matter or information for ready reference by the recipient of the mailed package.

While I have described the separation lines in both forms of the invention as comprising perforations, it will be evident that such separation lines may be provided in other ways. The material may be weakened in any known manner along the separation lines. Partial cutting of the material and complete cutting with subsequent fastening of the parts together to provide a separation line are within the contemplation of providing weakened portions for separation of the parts. The weakening must be such as to make it easy to separate the envelope closing parts of the file envelope from the front and back walls that produce the file folder. In the claims I use the term "weakened portions" to include the above and equivalent connections between the parts whereby they may be readily separated.

From the foregoing description it is believed that the nature of the present invention and its use will be readily apparent to those skilled in this art.

Having thus described my invention, what I claim as new and desire to secure by Letters Patent is:

1. In a file envelope, a paper sheet folded intermediate its ends to provide front and back walls, one end of said sheet comprising a flap folded into overlapped relation to the other end of the sheet and attached thereto, said front and back walls being secured to each other along one side edge thereof, one of said walls having a closing flap secured to the other side edge thereof, said sheet having weakened separation lines at the side edges that are secured together and along the two opposite ends, the weakened line in the overlapped one of said walls adjacent the first named flap being located inwardly of the zone of attachment of the flap whereby the flap

and the attaching portion of said overlapped wall may be removed together.

2. In a file envelope, a paper sheet folded intermediate its ends to provide front and back walls, one end of said sheet comprising a flap folded into overlapped relation to the other end of the sheet and attached thereto, said front and back walls being secured to each other along one side edge thereof, one of said walls having a closing flap secured to the other side edge thereof, said sheet having weakened separation lines at the side edges that are secured together and along the two opposite ends, the weakened line in the overlapped one of said walls adjacent the first named flap being located inwardly of the zone of attachment of the flap, and the weakened separation lines including a line along the other end of the sheet that coincides with the line of attachment of the attached flap for at least a portion of its length whereby the flap and the attaching portion of said overlapped wall may be removed together.

3. In a file envelope, a paper sheet folded intermediate its ends to provide front and back walls, one end of said sheet comprising a flap folded into overlapped relation to the other end of the sheet and attached thereto, said front and back walls being secured to each other along one side edge thereof and one of the walls carrying a side edge flap that overlaps the side edge of the other wall and is attached thereto, one of said walls having a closing flap secured to the other side edge thereof, said sheet having weakened separation lines at the side edges that are secured together and along the ends, the weakened line in the overlapped one of said walls being located inwardly of the zone of attachment of the flap whereby the flap and the attaching portion of said overlapped wall may be removed together, one of the weakened separation lines at the side edges being along the junction of the attached flap with its supporting wall and the other separation line being in the overlapped wall inwardly of the attachment of the flap thereto.

4. In a file envelope, a paper sheet folded intermediate its ends to provide front and back walls, one end of said sheet comprising a flap folded into overlapped relation to the other end of the sheet and attached thereto, said front and back walls being secured to each other along one side edge thereof to form an envelope pocket, one of said walls having a closing flap secured to the other side edge thereof, the flaps, the overlapped portion and the secured together portions of said envelope being joined to said front and back walls by weakened portions establishing separating lines for ready removal of said flaps and overlapped and secured together portions from the front and back walls whereby to provide a file folder with single thickness front and back walls.

5. In a file envelope, a paper sheet folded intermediate its ends to provide front and back walls, one end of said sheet comprising a flap folded into overlapped relation to the other end of the sheet and attached thereto, said front and back walls being secured to each other along one side edge thereof to form an envelope pocket, one of said walls having a closing flap secured to the other side edge thereof, the flaps, the overlapped portion and the secured together portions of said envelope being joined to said front and back walls by weakened portions establishing separating lines for ready removal of said flaps and overlapped and secured together portions from the

front and back walls whereby to provide a file folder with single thickness front and back walls, the separating lines at the top edge of the front wall being farther from the edge of said sheet than those at the top edge of the back wall thereby providing the folder with a back wall higher than the front wall.

6. In a file envelope, a paper sheet folded intermediate its ends to provide front and back walls, one end of said sheet comprising a flap folded into overlapped relation to the other end of the sheet and attached thereto, said front and back walls being secured to each other along one side edge thereof to form an envelope pocket, one of said walls having a closing flap secured to the other side edge thereof, the flaps and the overlapped and secured together portions of said envelope being joined to said front and back walls by weakened portions establishing separating lines for ready removal of said flaps and overlapped and secured together portions from the front and back walls whereby to provide a file folder with single thickness front and back walls, the separating lines at the top edge and one side edge of the front wall being farther from the edge of said sheet than those at the top edge and one

side edge of the back wall thereby providing the folder with a back wall higher and wider than the front wall.

7. In a file envelope, a paper sheet folded intermediate its ends to provide front and back walls, one end of said sheet comprising a flap folded into overlapped relation to the other end of the sheet and attached thereto, said front and back walls being secured to each other along one side edge thereof to form an envelope pocket, one of said walls having a closing flap secured to the other side edge thereof, the flaps and the overlapped and secured together portions of said envelope being joined to said front and back walls by weakened portions establishing separating lines for ready removal of said flaps and overlapped and secured together portions from the front and back walls whereby to provide a file folder with single thickness front and back walls, the separating line at one side edge of the front wall being farther from the edge of said sheet than the line at the corresponding side edge of the back wall thereby providing the folder with a back wall wider than the front wall.

WILBUR R. CHAPEL.
